UNITED STATES PATENT OFFICE.

HENRY J. CARRIGAN, OF BUFFALO, NEW YORK, ASSIGNOR TO WILLIAM H. MOUNT, OF BUFFALO, NEW YORK.

GRAVITY-LEVEL.

No. 909,060.

Specification of Letters Patent.

Patented Jan. 5, 1909.

Application filed May 8, 1908. Serial No. 431,548.

To all whom it may concern:

Be it known that I, HENRY J. CARRIGAN, a citizen of the United States, residing at Buffalo, in the county of Erie and State of New York, have invented a certain new and useful Improvement in Gravity-Levels, of which the following is a specification.

This invention relates to an improved gravity-level and the object of the invention is to provide a universal movement for the indicating hand.

The invention also relates to certain details of construction of the level which will be hereinafter described and claimed reference being had to the accompanying drawings, in which,—

Figure 1 is a central longitudinal section through the improved gravity level on line *a* *a*, Fig. 3, the indicating needle being shown in elevation. Fig. 2 is a central vertical transverse section through the improved gravity level on line *b* *b*, Fig. 3 the indicating needle being shown in elevation. Fig. 3 is a top plan view of the improved gravity level. Fig. 4 is a horizontal section through the improved gravity level on line *c* *c*, Fig. 1. Fig. 5 is an enlarged fragmentary section on line *d* *d*, Fig. 3. Fig. 6 is an enlarged fragmentary section through the mounting of the concavo-convex glass of the indicator. Fig. 7 is an enlarged fragmentary section through the oscillating mechanism showing one of the cone bearings. Fig. 8 is a view of another form of the oscillating mechanism partially in section.

In referring to the drawings in detail like numerals designate like parts.

In the accompanying drawings a fragment 1, of a suitable bar or the like is shown in an opening 2 of which the improved gravity level is mounted. The opening 2 is circular in form and extends vertically through from the top to the bottom of the bar which is preferably rectangular in form and of wood.

The bevel frame consists of an annular lower ring 3, an upper ring 4 of slightly smaller circumference than the lower ring and located in a plane above the lower ring, opposed angular frame bars 5 which are fastened rigidly to opposite sides of the rings 3 and 4 and have outwardly extending horizontal portions 6 in which the lower ends of bolts 7 screw. The wood at the lower part

of the opening is cut away on opposite sides as shown at 8 in Fig. 1 to provide openings 55 to receive the horizontal portions.

The oscillating mechanism comprises a ring 9 which is arranged concentrically within the upper ring 4 and has two oppositely extending cone points 10 which fit in conical recesses in the inner ends of supporting screws 11 located on opposite sides of the ring 4, an indicating needle 12 having a weight 13 at its lower end and an intermediate horizontal cross beam 14 provided with conical ends which fit in the conical recesses in the inner ends of screws 15 mounted in the ring 9. The screws 15 are located at right angles to the screws 11 so that the needle 12 can swing universally in any direction on either the axis of its cross beam or the axis of the ring 9 as the bar 1 is turned to indicate the degree of inclination. The screws 11 and 15 are preferably of similar diameter throughout their length with screw threads cut uniformly from end to end as shown in Figs. 1, 2, 4 and 7, and have a slot for the reception of a screw driver at one end and a conical recess at the opposite end. The screws 11 and 15 are adjustable to take up wear or lost motion and also to enable the indicating needle 12, to be centered accurately. The weight 13 is preferably bell shaped as shown in Figs. 1 and 2.

A ring 16 of light thin metal and of angular form in cross section is mounted upon the upper ends of the frame bars 5 and forms a support for the top cover of the level. The top cover 17 of the level is of glass or other transparent material and is of concavo-convex form being curved to correspond to the curve of oscillation of the upper extremity of the indicating needle 12 so that the needle will oscillate in close proximity to the top cover. The concavo-convex cover is flattened at its edge as indicated at 18 and a metal rim 19 is fitted on the edge of the cover and held in place by a spring ring 20. The rim 19 has a depending flange 21 which seats within the upper portion of the ring 16 as shown in Fig. 6 and an outer metal protector 22 of annular form is fitted upon the flattened edge of the glass cover. The protector 22 has a top horizontal flange 23 which is set flush in the top surface of the bar 1 around the opening 2 and fastened in place by screws

24. The heads of the bolts 7 are sunk in recesses 25 in the flange 23, see Fig. 3 and the lower surfaces of the heads are rounded as shown at 26, in Fig. 5 so that the bolts may 5 turn slightly. The openings 27 through which the bolts 7 pass are made slightly larger than the shanks of the bolts to permit a slight lateral movement to the bolts for the purposes of adjustment. The level is 10 adjusted so as to be perfectly true in its position in the bar 1, by the bolts 7 and transverse adjusting screws 28 which pass horizontally through the sides of the bar and engage against opposite sides of the ring 3, as shown 15 in Fig. 2. The screws 28 are located between and at right angles to the bolts 7 to provide for adjustment in any direction and thus allow the instrument to be brought to absolute 20 trueness.
- 20 A scale for indicating the degree of inclination is cut or otherwise formed in the cover and consists of a series of concentric circular rings 29 and a series of figures 30 indicating the degree of each ring as shown in Fig. 3.
- 25 The advantages of this improved level reside in its accuracy and delicacy of oscillation, its unusual manner of indicating, the manner in which it can be trued and the way

in which it can be assembled or dismounted or adjusted.

I claim as my invention—

In a gravity level, a frame including a stationary outer ring, a smaller inner ring located concentrically within the outer ring and having oppositely extending cone projections, screws adjustably fitted in opposite sides of the stationary outer ring having recesses in which the cone projections of the inner ring engage to pivotally support the inner ring in the outer ring, a vertical indicating needle having a weighted lower end and an intermediate cross bar having opposite cone ends, screws adjustably fitted in opposite sides of the inner ring and at substantially right angles to the screws in the outer ring and having recesses in which the cone ends of the cross bar of the indicating needle engage to pivotally support the indicating needle in the inner ring and an indicating scale over the indicating needle, substantially as set forth.

HENRY J. CARRIGAN.
